UNITED STATES PATENT OFFICE.

CHARLES E. BEST, OF CANTON, OHIO.

EXPLOSIVE-ENGINE-CRANKING DEVICE.

1,040,495.

Specification of Letters Patent.

Patented Oct. 8, 1912.

Application filed March 20, 1911. Serial No. 615,469.

To all whom it may concern:

Be it known that I, CHARLES E. BEST, a citizen of the United States, residing at Canton, in the county of Stark and State of Ohio, have invented a new and useful Improvement in Explosive-Engine-Cranking Devices, of which the following is a specification.

This invention relates to hand operated devices for starting internal combustion or explosive gas engines, the pistons of which must ordinarily be moved to compress the explosive charge to effect the internal explosion and start the automatic operation of the engine. Such engines are operated ordinarily by means of a crank, lever or the like applied to the engine crank-shaft or other shaft run by the engine. The crank lever or like appliance is operated by hand during which operation it frequently happens that the charge is fired prematurely, owing to various causes such for instance as a faulty igniter or overheating of the cylinder, thereby, causing a sudden reverse or backward rotation of the engine shaft such sudden and violent rotation of the engine shaft, if imparted to the starting crank or device when the operator is exerting pressure thereon to bring about the forward rotation of the engine shaft, is very liable to and frequently does injure the operator.

The objects of my present invention are to provide a desirable device by means of which the engine-shaft can be rotated forwardly to start the engine, but is positively prevented from taking any part in the reverse rotation of the engine-shaft, in the event of a premature explosion, and further to construct the starting device so that it will be thrown out of action by the forward action of the engine-shaft, after the engine has been started. These objects together with other objects readily apparent to those skilled in the art I attain by the construction illustrated in the accompanying drawings, although my invention may be embodied in a variety of other mechanical forms, the construction illustrated being chosen by way of example.

In the accompanying drawings—Figure 1 is a side elevation showing the different parts properly assembled showing the inclosed case in section. Fig. 2 is a detached view of the driving gear and its clutch member. Fig. 3 is a detached perspective view of the releasing pawl. Fig. 4 is a de-

tached perspective view of the key pawl. Fig. 5 is a detached view of the rotatable cage showing the releasing pawl connected thereto. Fig. 6 is a detached perspective view of the crank shaft notched disk. Fig. 7 is a view showing a portion of the cage housing, the cage, the releasing pawl and key pawl showing said pawls in position when the engine starts backward by premature explosion or what is commonly known as "back fire." Fig. 8 is a vertical section showing the parts in the same position as shown in Fig. 1. Fig. 9 is a section taken on line 8—8, Fig. 8.

Similar numerals of reference indicate corresponding parts in all the figures of the drawings.

In the accompanying drawings, 1 represents the base which is attached to the automobile frame or body at such a place that the cranking devices will be in proper relative position with reference to the engine shaft 2 and to which shaft connection is made to manually compress the explosive discharge to effect the initial explosion by means of the crank 3 and intermediate mechanism between said crank and the engine-shaft 2. The base 1 is provided with the spaced supports 4 and 5, which are preferably formed integral with the base, but said supports can be made separate from the base and attached in any convenient and well known manner.

In the support 5 is journaled the hollow shaft 6, which hollow shaft is provided with the recesses 7, which recesses are for the purpose of receiving the pin 8, which pin is fixed to the engine shaft 2. The engine shaft coupling devices are of the usual construction and form no specific part of the present invention. It will be understood that some means must be provided to temporarily and rotatably connect the hollow shaft 6 and the engine shaft 2 together so that they may be rotated in unison when it is desired to operate the crank to start the engine. Within the hollow shaft 6 is located a portion of the crank shaft 9, which crank shaft is journaled in the support 4 and a portion of the hollow shaft mounted upon said crank shaft.

Upon the crank shaft 9 is loosely mounted the gear wheel 10, which gear wheel meshes with the gear wheel 11, said gear wheel being fixed to the shaft 12. Upon the shaft 12 is also fixedly mounted the gear wheel 13, which gear wheel meshes with the gear

wheel 14 fixed to the hollow shaft 6. When it is desired to actuate the engine-shaft 2 to start the engine the crank shaft 9 is slipped endwise and toward the engine-shaft 2, thereby rotatably connecting the hollow shaft 6 with the engine shaft 2. When force is applied to the crank 3 to rotate the shaft 9 the releasing pawl 15 and the key pawl 16 are in the positions shown in Fig. 9 and in which position the rib 17 upon the key pawl 16 is seated in one of the notches 18 and 19 formed in the disks 20 and 21, the disk 20 being securely mounted upon the crank shaft 9 and the disk 21 being fixed to or connected with the gear wheel 10 and is also loosely mounted upon the crank shaft 9. It will be understood that when the rib 17 is seated in the proper grooves 18 and 19, the disks 20 and 21 will be rotatably connected together, but it will be understood that the notches 18 and 19 or two of them, one upon each disk must be brought into alignment with each other so that the rib or coupling key 17 can and will rotatably connect the two disks 20 and 21 together and when so connected together rotary motion will be imparted to the gear wheel 10, which in turn imparts rotary motion to the gear wheel 11, the shaft 12, the gear wheel 13 and the gear wheel 14, and by reason of the gear wheel 14 being fixed to the hollow shaft 6 rotary motion will be imparted to said hollow shaft 6. When the parts are in the position shown in Fig. 9 the crank 9 can be actuated in the direction to start the engine.

Upon the hollow shaft 6 is fixedly mounted the disk or wheel 22 to which disk or wheel is attached the ring or housing 23, the inner periphery of which housing or ring is provided with the ratchet teeth 24. If in the event a premature explosion of the engine takes place while the crank is being actuated to start the engine, such backward movement will impart a backward movement to the hollow shaft 6 and in turn to the wheel or disk 22 and such backward movement will rock the releasing pawl 15 upon its pivotal point 25, owing to the fact that when a backward movement of the ring 23 takes place the tooth adjacent the pointed end of the releasing pawl will engage said pointed end and rock it or in other words carry said pawl into such a position that its pointed end will be seated into a recess between two adjacent teeth 24 and bring said pawl into the position illustrated in Fig. 7 and when brought into that position the rounded end 26 of the releasing pawl 15 will press the tail 27 of the key pawl 16, thereby rocking said key pawl 16 upon its pivotal point 28 and lifting the rib 17 out of the notches 18 and 19, thereby disconnecting the crank-shaft 9 from the hollow shaft 6 and when so disconnected

any backward motion of the engine will not be communicated to the handle 3, thereby removing all danger resultant from the backward action of the engine during the time the engine is being operated upon to be started or what is commonly known "cranked".

For the purpose of holding the releasing pawl 15, and the key pawl 16 in proper relationship with reference to the housing or ring 23 and the disks 20 and 21, the plates 29 and 30 are provided, which plates are spaced apart and held in proper spaced relationship with reference to each other by the shouldered rivets 31 or their equivalents. The plates 29 and 30 constitute what might be termed a cage which is located concentrically with the ring or casing 23 and the disks 20 and 21, said cage shown located in proper relationship in Figs. 8 and 9.

For the purpose of preventing any accidental displacement of the key pawl 16 when the rib 17 is brought into engagement with the proper grooves 18 and 19, the spring 32 is provided which spring has a tendency to push the tail 27 of the key pawl 16 outward and hold the rib 17 in proper engagement with the grooves, said spring being fixed at one of its ends to the cage and its opposite end connected to the tail 27 by means of the pin 33 or its equivalent. For the purpose of preventing any accidental displacement of the releasing key 15 or more specifically to hold the pointed end of said releasing pawl in such a position that it will be engaged by one of the ratchet teeth 24, the spring 34 is provided, which spring is connected in substantially the same manner as the spring 32, said spring also acting to hold the releasing pawl so that it will be in position at all times to be rocked by any backward movement of the ring or housing 23. For the purpose of bringing the grooves 18 and 19 into proper alignment so that the rib 17 can be forced into said grooves to rotatably lock the disks 20 and 21 together the plate 30 is provided with the ratchet teeth 35, which ratchet teeth engage the catch-pin 36, which catch-pin is slidably mounted in the disk 20, and is normally held in extended position by means of the spring 37.

It will be understood that a backward movement of the crank shaft 9 will impart a backward movement of the disk 20 and when any set of grooves 18 and 19 come in proper alignment the key 17 will be forced into the position illustrated in Fig. 9 and when a forward movement is given to the crank shaft 9 after it has been properly coupled up to the engine shaft 2 by means of the hollow shaft 6 and the various parts the catch pin 36 will ride over the ratchet teeth 35 by reason of the beveled end 38 of the catch pin 36 riding upon the

ratchet teeth. The devices just above described are more specifically designed to rotatably pick up the disk 21 and the gear wheel 10 after which the shaft 9 is given an end movement toward the engine shaft 2.

For the purpose of imparting an end movement to the shaft 6 at the same time an end movement is imparted to the crank shaft 9 a collar 39 is provided, which 10 collar is fixed to the crank shaft 9 in any convenient and well known manner and acts to force all of the parts carried by the hollow shaft 6 and the shaft 9 endwise.

It will be understood that the gear wheels 15 11 and 13 should be formed of sufficient width that the wheels meshing with said gear wheels will not be thrown out of mesh by the reciprocating movement of the crank shaft 9 and the hollow shaft 6. For the 20 purpose of automatically forcing the hollow shaft 6 endwise after the engine proper has been started the spring 40 is provided, which spring has a tendency to normally hold the hollow shaft 6 and the crank shaft 9 in their 25 outermost position or more specifically away from the engine shaft 2.

It will be understood that by reason of the various gear wheels 10, 11, 13 and 14 the hollow shaft 6 will rotate at a greater 30 speed than the crank shaft 9 and consequently the wheel 22 and its integral and attached ring 23 will also rotate faster by reason of the wheel 22 being fixed to the hollow shaft 6, so that after the crank 35 shaft 9 is rotated the ratchet teeth will ride over or pass over the releasing pawl 15, owing to the fact that the differential rotary movement as between the cage made up of the disks 30 and 31 and the ratchet 40 toothed ring 23. For the purpose of protecting the various devices or more specifically making a proper cover for the same the casing or housing 41 is provided, which 45 may be attached to the frame 1 in any convenient and well known manner.

Having fully described my invention what I claim as new and desire to secure by Letters Patent, is—

1. In an explosive engine cranking device, 50 the combination of a suitable frame, a hollow shaft journaled in said frame, a crank shaft journaled in said frame, said crank shaft extended into the hollow shaft, a gear wheel loosely mounted upon the crank shaft 55 and a gear wheel fixed to the hollow shaft, gear wheels adapted to mesh with the gear wheel loosely mounted upon the crank shaft and the gear wheel fixedly mounted upon the hollow shaft, a disk provided with a 60 ring, said ring provided with ratchet teeth, said disk fixed to and rotatable with the hollow shaft, a cage located concentrically with the ring provided with the ratchet teeth, said cage provided with pawls, one 65 of said pawls adapted for engagement with

the ratchet teeth, disks provided with grooves, one of said disks loosely mounted upon the crank shaft and fixed to the gear loosely mounted upon the crank shaft and the other disk fixedly mounted to the crank 70 shaft and one of the pawls carried by the cage adapted for engagement with the disks, said crank shaft and hollow shaft slidably mounted in the frame, substantially as and for the purpose specified. 75

2. In an explosive engine cranking device, the combination of a frame, a hollow shaft and a crank shaft telescopically connected together and rotatably and slidably mounted in the frame, clutch mechanism adapted to 80 rotatably couple the hollow shaft to the engine shaft, said hollow shaft provided with a fixed gear wheel and a wheel having internal ratchet teeth, a gear wheel loosely mounted upon the crank shaft and gear 85 wheels located intermediate the gear wheel fixed to the hollow shaft, and the loosely mounted gear wheel upon the crank shaft, a grooved disk fixed to and rotatable with the loosely mounted gear wheel upon the 90 crank shaft, a disk fixedly mounted to said crank shaft, said disks provided with grooves upon the peripheries, said grooves adapted for alinement, a cage loosely mounted concentric with the crank shaft, a 95 key pawl carried by said cage and adapted for engagement with the grooves in the disks and a releasing pawl adapted for engagement with the ratchet teeth of the wheel fixed to and rotatable with the hollow shaft, substantially as and for the purpose specified. 100

3. In an explosive engine, cranking shaft, the combination of a frame, a hollow shaft and a crank shaft telescopically connected together and rotatably and slidably mounted in the frame, clutch mechanism adapted to 105 rotatably couple the hollow shaft to an engine shaft, said hollow shaft provided with a fixed gear wheel and a wheel having internal ratchet teeth, a gear wheel loosely mounted upon the crank shaft and gear wheels located intermediate the gear 110 wheels fixed to the hollow shaft, and the loosely mounted gear wheel upon the crank shaft, a grooved disk rotatable with the loosely mounted gear wheel upon the crank shaft, a grooved disk fixedly mounted to said crank shaft, said disks provided with grooves upon their peripheries, said grooves adapted for alinement, a cage provided with internal teeth, pawls carried by said cage, one of said pawls adapted for engagement with the disks provided with the grooves and the other pawl adapted for engagement 115 with the ratchet teeth of the wheel fixed to and rotatable with the hollow shaft and a spring adapted to normally hold the key pawl in engagement with the alined grooves of the disk and a releasing pawl carried by 120 125 130

the disk fixed to the crank shaft, said releasing pawl adapted for engagement with the teeth of the cage, substantially as and for the purpose specified.

5. 4. In an explosive engine cranking device, the combination of a frame, shafts rotatably and slidably mounted in the frame, one of said shafts provided with a crank, an engine shaft, and one of the sliding shafts adapted 10 to be coupled to the engine shaft, means for imparting differential rotary movement between the crank shaft and the shaft adapted to be coupled to the engine shaft, a cage, said cage made up of spaced plates, one of 15 the plates provided with inward extending teeth, a releasing pawl and a key pawl carried by said cage and rotatable therewith, notched disks, one on the crank shaft and one connected to the means for imparting 20 differential rotary movement, located side by side and concentric with the crank shaft, said notched disks adapted to receive the key of the key pawl and means for holding the key pawl in engagement with the notches 25 of the notched disks, substantially as and for the purpose specified.

5. In an explosive engine cranking device, the combination of a frame, shafts rotatably and slidably mounted in the frame, one of 30 said shafts adapted to be coupled to an engine shaft and the other shaft provided with a crank, a gear wheel loosely mounted upon the shaft provided with a crank, a gear wheel fixed to the shaft adapted to be coupled to the engine shaft and gear wheels located intermediate the aforesaid gear wheels, a disk rotatable with the gear wheel loosely mounted upon the crank shaft, a disk fixed to and rotatable with the crank shaft, said 35 disks provided with grooves located upon their peripheries, a wheel fixed to the crank shaft adapted to be connected to the engine shaft, said wheel provided with a lateral ring, the inner periphery of which is provided with ratchet teeth, a cage located concentrically with the disks provided with the groove and the ring provided with the ratchet teeth, said cage provided with releasing and key pawls respectively, said key pawl 40 adapted to rotatably couple the loosely mounted and fixedly mounted disks together and the releasing pawl adapted to disconnect the disks by a backward movement of the ring provided with the ratchet teeth, 45 substantially as and for the purpose specified.

5. In an explosive engine cranking device, the combination of a frame, shafts rotatably and slidably mounted in the frame, one of 60 said shafts adapted to be coupled to an engine shaft and the other shaft provided with a crank, a gear wheel loosely mounted upon the shaft provided with the crank, a disk rotatable with said gear wheel loosely mounted 65 upon the crank shaft, a disk fixed to and

rotatable with the crank shaft, said disk provided with grooves located upon their peripheries, a wheel fixed to the shaft adapted to be connected to the engine shaft, said wheel provided with a lateral ring, the inner periphery of which is provided with ratchet teeth, a cage located concentrically with the disks provided with the groove and the ring provided with the ratchet teeth, said cage provided with a releasing and key pawl 70 respectively, said key pawl adapted to rotatably couple the loosely mounted and fixedly mounted disks together and the releasing pawl adapted to disconnect the disks by a backward movement of the ring provided with the ratchet teeth, and gear wheels 75 adapted to impart differential rotary movement as between the crank shaft and the shaft adapted to be connected to the engine, substantially as and for the purpose speci- 80 fied.

7. In an explosive engine cranking device, the combination of a frame, shafts rotatably and slidably mounted in the frame, one of said shafts adapted to be coupled to the engine shaft and the other shaft provided with a crank, a gear wheel loosely mounted upon the crank shaft and a gear wheel fixedly mounted upon the other slideable shaft and rotatable therewith, a shaft provided with 90 two gear wheels fixedly mounted upon said shaft, said gear wheels adapted to mesh with the aforesaid gear wheels upon the slideable shafts, a disk fixedly mounted upon the crank shaft, and means for rotatably connecting said disk with said loosely mounted gear wheel upon the crank shaft, substantially as and for the purpose specified.

8. In an explosive engine cranking device, the combination of a frame, shafts rotatably and slidably mounted in the frame, the shaft adapted to be coupled to the engine shaft provided with a wheel having internal ratchet teeth, a cage located concentrically with the wheel provided with the internal ratchet teeth, said cage consisting of plates held in proper spaced parallel relationship, one of said plates provided with internal ratchet teeth, a disk fixed to one of the shafts journaled in the frame, said disk provided 110 with a pin adapted for contact with the ratchet teeth formed in one of the cage plates and adapted to rotate said cage in one direction, a gear wheel loosely mounted upon the crank shaft, a disk rotatable with the gear wheel loosely mounted upon the crank shaft, means for rotatably coupling the disks together and means for uncoupling said disks by the backward movement of the shaft coupled to the engine shaft and 115 means for imparting differential rotary movement between the crank and the shaft connected to the engine, substantially as and for the purpose specified.

9. In an explosive engine cranking de- 120

vice, the combination of a suitable frame, shafts journaled and slidably mounted in said frame, one of said shafts adapted to be coupled to an engine shaft and the other 5 provided with a crank, a gear wheel loosely mounted upon said crank shaft, a gear wheel fixed to the shaft adapted to be coupled to the engine shaft, a shaft spaced from the slidably mounted shafts 10 and provided with gear wheels, adapted to mesh with the gear wheels located upon the crank shaft and the engine coupling shaft respectively, a wheel provided with internal ratchet teeth located 15 concentric with the crank shaft, a cage located concentrically with the wheel provided with the ratchet teeth, disks located concentrically with the cage, one disk fixed

to the crank shaft and the other loosely mounted thereon and fixed to the loosely 20 mounted gear wheel located upon the crank shaft, pawls carried by the cage, one of the pawls adapted to rotatably lock the aforesaid disks together and the other pawl adapted to release the engaging pawl and 25 said disks by the backward movement of the wheel provided with the internal ratchet teeth, as and for the purpose specified.

In testimony that I claim the above, I have hereunto subscribed my name in the 30 presence of two witnesses.

CHARLES E. BEST.
